Primary Examiner — T Chase Nelson*Assistant Examiner* — Kelly L Gross(74) *Attorney, Agent, or Firm* — KandareIP, LLC; Anthony Kandare(57) **CLAIM**

The ornamental design for an ovoidal platform of a DAP unweighting system, as shown and described.

DESCRIPTION

FIG. 1 is a front perspective view of an ovoidal platform of a DAP unweighting system showing my new design; FIG. 2 is a front view thereof; FIG. 3 is a rear view thereof; FIG. 4 is a right side view thereof; FIG. 5 is a left side view thereof; FIG. 6 is a top view thereof; and, FIG. 7 is a front perspective view thereof depicted with an example user in a usage condition.

The broken lines immediately adjacent to the shaded area define bounds of the claimed design and form no part thereof. The broken line showing of the remainder of the differential air pressure unweighting system and of the example user form no part of the claimed design.
